UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
LONDON, ENGLAND.

PERCUSSIVE FIRING MECHANISM OF ORDNANCE.

1,302,529.

Specification of Letters Patent.

Patented May 6, 1919.

Original application filed April 16, 1915, Serial No. 21,933. Divided and this application filed July 14, 1915.
Serial No. 39,924.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Percussive Firing Mechanism of Ordnance, 10 of which the following is a specification.

This application is a division of our co-pending application Serial No. 21933, filed April 16, 1915.

This invention relates to percussive firing mechanism of the kind in which the cradle carries a firing shaft adapted to be actuated through the intermediary of a pivoted member from a trigger or firing handle mounted on or carried by a member pivoted on the gun carriage in a position which is some distance removed from the axis of the gun trunnions, and the chief object of the present invention is to provide improved means for actuating a rotary firing shaft without 25 its being necessary to make the said shaft telescopic or provide it with universal joints.

In order that the said invention may be clearly understood and readily carried into effect we will describe the same more fully 30 with reference to the accompanying drawings, in which:

Figure 1 is a sectional end elevation showing a constructional form of the improved firing mechanism;

35 Figs. 2 and 3 are respectively a sectional side elevation, and a sectional end elevation showing on a larger scale the improved firing mechanism.

A is the gun cradle, A' one of the trunnions, B the carriage, C the trigger or firing handle, and D the rotary firing shaft. E represents a member interposed between the trigger or firing handle and the rotary firing shaft, this member being longitudinally 45 hinged at e e to the carriage.

In the examples shown the trigger C is carried by the handle of the elevating or training hand wheel or lever which is mounted on the carriage in a position which

50 is not eccentric with the gun trunnion. This trigger actuates a sliding rod C' arranged

axially within the boss of the hand wheel as is well understood.

In the example shown the member E is in the form of a downwardly extending arm 55 E' and an inwardly projecting ledge E². The sliding rod C' rests in contact with the outer surface of the arm E' and the ledge E² has a curved surface which as shown in Fig. 2 is concentric with the gun trunnions. 60 In contact with this curved surface is a roller carried by an arm D' on the rotary firing shaft D. The hinges e e may be supported in roller or ball bearings.

The rotary firing shaft D may actuate a 65 spring plunger for engaging with a sleeve carried by the gun in a similar manner to that set forth in specification of our prior British Patent No. 16216 of 1911.

What we claim and desire to secure by 70 Letters Patent of the United States is:—

1. In a percussive firing mechanism for ordnance, the combination with the manually operated firing device arranged on the gun carriage in a position which is some 75 distance removed from the gun trunnions, of a rotary firing shaft, a member interposed between said firing device and the rotary firing shaft and having an operating surface concentric with the gun trunnions, 80 and means for pivotally supporting said member longitudinally with respect to the gun.

2. In a percussive firing mechanism for ordnance, the combination with the manually operated firing device arranged on the gun carriage in a position which is some distance removed from the gun trunnions, of a rotary firing shaft, a member having 85 a curved ledge interposed between said firing device and the rotary firing shaft, the curved surface of this ledge being concentric with the gun trunnions, and means for pivotally supporting said member longitudinally with respect to the gun. 90

In testimony whereof we affix our signatures.

ARTHUR TREVOR DAWSON.
GEORGE THOMAS BUCKHAM.

Witnesses:

HENRY KING,
JNO. R. CASWELL.
